UNITED STATES PATENT OFFICE.

GEORGE L. ROWEKAMP, OF WINONA, MINNESOTA.

VAPOR-GENERATING BURNER.

1,215,712.

Specification of Letters Patent. Patented Feb. 13, 1917.

Application filed April 24, 1916. Serial No. 93,238.

To all whom it may concern:

Be it known that I, GEORGE L. ROWEKAMP, a citizen of the United States, residing at Winona, in the county of Winona and State 5 of Minnesota, have invented certain new and useful Improvements in Vapor-Generating Burners, of which the following is a specification, reference being had to the accompanying drawings.

10 This invention relates to devices for generating inflammable vapor or gas and burning this vapor or gas, and particularly to devices peculiarly intended for generating inflammable gas or vapor from gasoline or like 15 hydrocarbons.

The general object of the invention is the provision of a mechanism to this end, so constructed that it may be used in connection with all "hollow wire" lighting systems 20 and which is capable of being used with gasoline lamps, lanterns, stoves, or in a large variety of other circumstances.

A further object of the invention is the provision of a generator and burner of this 25 character wherein the generator is kept constantly heated and in a condition to generate gas and wherein the mere opening of communication between the generator and the burner will immediately cause the ignition 30 of the gas issuing from the generator to the burner.

A further object of the invention is the provision of a very simple mechanism to this end which may be readily taken apart for 35 cleaning and readily assembled, and wherein provision is made for a very delicate regulation of the torch or auxiliary burner which heats the generating chamber and of the gas passing into the main burner.

40 Other objects will appear in the course of the following description.

My invention is illustrated in the accompanying drawings, wherein:

Figure 1 is a top plan view of a gas generating burner constructed in accordance 45 with my invention;

Fig. 2 is a section on the line 2-2 of Fig. 1;

Fig. 3 is a section on the line 3-3 of 50 Fig. 1;

Fig. 4 is a section on the line 4-4 of Fig. 1;

Fig. 5 is an elevation of the valve 37 and its actuating means; and

55 Fig. 6 is a view showing my device adapted for heating.

Referring particularly to Fig. 2, 10 designates the generating chamber which consists of a cylindrical or tubular member closed at its opposite ends, this tubular member being in practice about two inches long. At one end this tubular member or generating chamber is formed with an upwardly extending nipple 11 from which extends an arcuately bent pipe 12 engaged with one 15 branch of a T-coupling 13. The other branch of this T-coupling is engaged with an arcuately bent depending pipe 14 which constitutes a shade support. The upper branch of the T-coupling 13 is connected to 20 an upwardly extending tube 15 which at its upper end has screw threaded engagement with a union 16 provided with a reducing coupling 17, the union providing means whereby the pipe 15 may be connected to the 25 coupling on the usual "hollow wire" 9 or feed pipe leading from any source of supply. The interior of the tubes 15 and 12 are filled with asbestos packing, designated 30 18, this packing extending down into the chamber 10. Just below the nipple 11 the chamber 10 is provided with a downwardly extending nipple 19 normally closed by a plug 20.

The generator 10, relatively adjacent the 35 nipple 11, is provided with the upwardly extending nipple 20 having an upwardly extending relatively small pipe 21 which at its upper end is connected to a T 22. From this T extends a downwardly curved pipe 23 which discharges against the generating 40 chamber 10. Preferably a hollow wire, as it is called, or a small tube, of copper or other like material and designated 24, is disposed within the tube 21 and extends upward into the T 22 and extends through the torch or auxiliary burner tube 23. This tube 23 is provided with one or more small intake 45 openings 25 whereby air may be mixed with the gas passing through the tube 24.

Controlling the passage of gas through 50 the tube 24 is a needle valve 26 which passes through a tubular valve guide 27 attached to one end of the T 22 and through a gland nut 28 connected to the hub 27. The stem of the needle valve is provided with a handle 29 whereby the needle valve may be manipulated to decrease or increase the amount of gas flowing into the auxiliary tube 23. The members 21 and 28 together constitute a 55 torch discharging with considerable pressure against the wall of the generating chamber.

ber and heating the contents of the generating chamber to thereby cause a vaporization of the liquid fuel passing into this chamber by way of the asbestos wick 18.

5 On the opposite end of the chamber 10 from the nipple 11 is an upwardly extending nipple 30 from which extends an upwardly extending tube 31 engaging at its end with one branch of a T 32. The opposite end of this T is engaged with an upwardly and then downwardly curved burner supporting pipe 33 which at its lower end carries any suitable burner, as for instance, the mantle 34, this mantle being held in place by means of supporting wires 35. Within the tube 31 there is disposed a generator pipe 36, and controlling the passage through this generator pipe is a longitudinally movable valve 37, the outer end of which is operatively engaged with a shaft 38. This shaft is slightly cranked on one end, as at 39, and a rotation of this shaft will therefore operate to shift the valve 37 in one direction or the other toward or from the generator pipe and to very delicately control the amount of gas passing through this pipe.

The shaft 38 is mounted in a guide tube 40 operatively engaged with a nipple 41. 30 The shaft passes through this guide tube and engaging the end of the guide tube is a gland nut 42. The extremity of the shaft 38 carries upon it the yoke or lever 43 connected to chains 44 whereby it may be operated. The 35 T 32 has an air intake tube 46 whereby air may be admitted into the interior of the mixing chamber constituted by the T 32, the mixed air and gas then passing through the mantle.

40 In the operation of this invention the liquid fuel passes down to the wick 18 and soaks this wick and this wick carries the liquid fuel into the generating chamber 10. The gas passing through the auxiliary 45 burner tube or torch 23 is continually burning and gives a very small blue flame which is directed against the generating tube 10. This small flame ejected from the pipe 23 is sufficient to cause the vaporization of the 50 liquid fuel entering the generator so that the generator is always filled with gas. Now if it be desired to ignite the gas in the burner or mantle, one or the other of the chains 44 is operated which retracts the 55 valve 37 and gas can pass from the generator out through the burner pipe 33 to the burner, as for instance, the mantle 34. The extremity of the pipe 23 is disposed relatively adjacent the mantle or burner and as a consequence will ignite the gas issuing from the 60 burner pipe 33. Thus there is no necessity of lighting this gas by any extraneous means. Simply opening the valve causes the gas to ignite and the closing of the valve cuts off the supply of gas to the burner. The amount

of flame directed against the generator may of course be regulated by regulating the needle valve 26.

In addition to having the generator heated at all times so that the burner will ignite the instant the controlling valve is opened, the construction which I have provided enables me to secure a light of from one candle power to four hundred candle power and thus it is possible to have either an extremely bright light or a very dim light, as may be wished for, depending upon the extent to which the valve is opened.

While I have illustrated this device as applied in connection with a mantle and in a lighting system, I wish it understood that it may also be used for heating systems, as for instance, in connection with a stove by changing the form of burner. Thus in Fig. 6 I have shown my device adapted to a heater. For this purpose the construction is inverted as illustrated in this figure. In this figure I have already shown the relative positions of the burner tube 33 and of the blow or glass tube 23. The burner 34^a in this case is a star-shaped burner and the blow tube 23 terminates between the arms of this burner. Otherwise than as thus indicated, the construction is the same as that illustrated in all the other figures.

Having described the invention, what I claim is:

1. In a gas generating burner of the character described, a generating chamber comprising a short section of pipe closed at its ends, a supply pipe having one end entering the side wall of the generating chamber adjacent one end thereof, a pipe extending outward from the middle of the generating chamber and having an extension leading therefrom and discharging against the exterior of the generating chamber, said pipe constituting an auxiliary burner or torch, a valve controlling the passage through the auxiliary burner, a main burner pipe extending outward from the side wall of the generating chamber and bent upon itself and extended toward and in a plane approximately parallel to the auxiliary burner pipe, a burner mounted on the end of said burner pipe, a valve for controlling passage of vapor from the generator into the burner pipe, and an air inlet nozzle in the burner pipe between the burner and the valve, the auxiliary burner pipe being disposed in relatively close relation to the main burner whereby the main burner may be ignited from the auxiliary burner.

2. In a gas generating burner, a generating chamber comprising a short section of pipe having a relatively small bore and a relatively thick wall and closed at its ends, a U-shaped pipe, one end of which is connected to the generating chamber adjacent one end thereof and constitutes a supply

5 pipe, a wick disposed in the supply pipe and extending into the generating chamber, the other branch of said U-shaped pipe constituting a support for a shade, a pipe extending outward from the middle of the generating chamber and having an extension leading therefrom and discharging against the exterior of the generating chamber and constituting an auxiliary burner or torch, a
10 valve controlling passage through this pipe, a main burner pipe extending out from the side wall of the generating chamber adjacent the auxiliary burner pipe and bent upon itself and extending toward the auxiliary burner pipe and in a plane approxi-
15 mately parallel thereto, a burner mounted on the end of the main burner pipe relatively adjacent the extremity of the auxiliary burner pipe, and a valve controlling the passage of the vapor into the main burner pipe, said main burner pipe being formed with an air inlet between the valve and the main burner.

In testimony whereof I hereunto affix my signature in the presence of two witnesses. 25

GEORGE L. ROWEKAMP.
